UNITED STATES PATENT OFFICE.

CHARLES W. KEMP, OF CHARLESTON, ILLINOIS.

ENGINEER'S ORDER BULLETIN-BOARD.

SPECIFICATION forming part of Letters Patent No. 444,211, dated January 6, 1891.

Application filed April 12, 1890. Serial No. 347,663. (No model.)

To all whom it may concern:

Be it known that I, CHARLES W. KEMP, a citizen of the United States, residing at Charleston, in the county of Coles and State of Illinois, have invented a new and useful Improvement 5 in Engineers' Order Bulletin-Boards, of which the following is a specification.

My invention relates to an improvement in order bulletin-boards for locomotive-engineers.

The object of my improvement is to provide a device for displaying and for temporarily filing the written orders received by a locomotive-engineer, the arrangement being such 15 that the immediate order under which he is running is displayed and previous orders are hidden and an alarm is sounded calling attention to the order each time the throttle-lever is moved.

20 The accompanying drawings illustrate my invention.

Figure 1 represents a front elevation showing the bulletin-board in position. Fig. 2 represents a side elevation of the same. Fig. 25 3 represents a back elevation. Fig. 4 represents a central vertical section of the bulletin-board without the alarm mechanism and shows the position of the parts when an order is being placed in position to be read. Fig. 5 represents a similar section, showing 30 the position of the parts when an order is being filed after it has served its purpose.

A is the body of the bulletin-board, having on its back side a transverse cleat *a*, which is secured to a standard *B*, erected on the boiler-head behind and above the throttle-lever *C*, the arrangement being such that the board *A* is rigidly supported in an upright position and slightly inclined backward.

40 *D* is a narrow bar forming an extension of the board *A* and secured to the lower edge thereof by a spring-hinge *E*, which holds the bar normally with a yielding force in the same plane as the board.

45 *F* is a heavy plate of glass, which is secured to the front face of bar *D* by a sheet-metal band *G* or in any other suitable manner, so that the glass plate moves rigidly with the bar. Plate *F* is of suitable size to cover the 50 face of board *A*, and the arrangement is such that the plate is held closely against the face

of the board with a yielding force by the spring-hinge *E*.

H is a removable backing for plate *F*, formed, preferably, of a sheet of tin-plate having three of its edges bent forwardly at substantially right angles, so as to embrace the top and the vertical edges of plate *F*. Backing *H* is inserted between plate *F* and the board *A*, and its purpose is to form an opaque 55 partition between the "dead orders" and those under which the engineer is running and to form a white ground against which the orders, which are usually written on tissue-paper, may be easily read. In using the bulletin-board the top of plate *F* is swung outward, as shown in Fig. 4, and the order *y* is spread against the outer surface of the tin-plate backing *H*, and the plate *F* on being 60 released holds the order closely and smoothly 65 in place, so that it can be easily read through the glass plate. When a new order is received, the old one is taken out from between plates *F* and *H*, and both plates are then 70 swung forward, as in Fig. 5, and the old order 75 is placed against the board *A*, where it is securely held by spring-hinge *E* when both plates are released.

For the purpose of directing the attention of the engineer and his fireman to the running-order, so as to prevent its being overlooked or forgotten, I connect an alarm-bell *i* with the throttle-lever *C* in such a manner that the movement of the lever will cause the bell to be struck. This is accomplished by 80 the following mechanism: A bracket *j*, having a forked backwardly-bent arm *k* and a forked forwardly-bent arm *l*, is secured to the back of board *A*. The bell *i* is also secured to the board. A hammer *m*, having at its 85 lower end a lug *n*, provided with a projecting lip *o*, is pivoted in the forked arm *k* in such a position that the upper end of the hammer will strike the bell. A lever *p*, having its outer end bent to form a double-inclined cam 90 *r*, is pivoted in the forked arm *l* in such a manner that the cam *r* lies in the path of movement of the throttle-lever, the other end of the lever being extended backward and having the trip-lever *s* pivoted thereto. Trip-lever *s* extends upward into the arm *k*, and 95 is provided near its upper end with a shoul-

der *t*, which is adapted to engage the projecting lip *o* on the hammer. The trip-lever is held in contact with the back edge of lug *n* by a spiral spring *u*, having its opposite ends attached, respectively, to the lug and the lever. Spring *u* operates, also, to hold up the rear end of the lever *p*, so that cam *r* is thereby held down against the throttle-lever *C*. When the throttle-lever is drawn forward, and again 10 when it is pushed backward, the front end of lever *p* is raised by the passage of the throttle-lever under cam *r*, and trip-lever *s* being pulled downward its shoulder *t* first engages and then slips off of lip *o* on lug *n* and causes 15 the hammer to strike the bell. For the purpose of preventing the ringing of the bell when there is no order a light arm *v*, having a hole *w*, is secured to the upper side of lever *p*, and the lever is thereby hung upon a pin *x*, 20 projecting from bar *D*, so that cam *r* is out of the path of movement of the throttle-lever, the arrangement being such that when the bar is tipped forward by the act of putting a new order in position arm *v* will slide off from 25 the pin, and the lever will without special attention be again in position to sound the bell.

By this device the "running-order" is kept in view where it can be easily read, while all other orders are securely taken care of, but 30 hid from view, and the attention of the engineer is called to the order every time he starts or stops his engine.

I claim as my invention—

1. In a bulletin-board, the combination of

the board, the bar forming an extension of the 35 board, the glass plate secured to the bar and arranged to cover the face of the board, and a spring-hinge connecting the bar and the board and arranged to hold the glass plate against the face of the board, substantially 40 as and for the purpose set forth.

2. In a bulletin-board, the combination of the board, the bar forming an extension of the board, the glass plate secured to the bar and arranged to cover the face of the board, the 45 spring-hinge connecting the bar and the board and arranged to hold the glass plate against the face of the board, and the opaque back- 50 ing-plate arranged between the glass plate and the board, all arranged to co-operate substantially as set forth.

3. The combination of the bulletin-board adapted to hold and display an order-sheet, the throttle-lever, the bent lever pivoted to the bulletin-board and arranged with its free 55 end in the path of said throttle-lever, the bell, the hammer arranged to strike the bell, and intermediate connecting mechanism connecting the bent lever and the hammer, all arranged to co-operate substantially as specified, 60 whereby the act of moving the throttle-lever operates to strike the bell and to call attention to the bulletin-board, as set forth.

CHARLES W. KEMP.
